[57] CLAIM

The ornamental design for a combined handle and es-
cutcheon, as shown and described.

DESCRIPTION

FIG. 1 is a perspective view of a combined handle and
escutcheon in accordance with the present design;

FIG. 2 is a front elevation thereof;

FIG. 3 is a bottom view thereof, the top being a mirror
image;

FIG. 4 is a left side elevation thereof;

FIG. 5 is a right side elevation thereof; and,

FIG. 6 is a rear elevation thereof.
